UNITED STATES PATENT OFFICE.

MICHAEL RAUGHTIGAN AND EDWIN OLDFIELD, OF NORWICH, CONN.

PICTURE-HANGER.

SPECIFICATION forming part of Letters Patent No. 227,055, dated April 27, 1880.

Application filed February 25, 1880.

To all whom it may concern:

Be it known that we, MICHAEL RAUGHTIGAN and EDWIN OLDFIELD, both of Norwich, in the county of New London, in the State of Connecticut, have invented a new and useful Improvement in Picture-Hangers, of which the following is a specification.

Our invention relates to hangers for picture-frames.

10 Among other forms of such devices is one in which a piece of wire is bent into the shape of an eye for the passage of the picture-cord and formed with a tongue acting as a stop to the cord.

15 Our invention is an improvement in the class of hangers referred to; and it consists in a picture-hanger having an eye for the passage of the picture-cord and a hook adapted to pierce the cord, the whole constructed of a single 20 piece of wire, so that the cord may be readily adjusted as to its length and be firmly retained in the desired position, while the article can be manufactured at a very low cost.

In the accompanying drawings, Figure 1 25 shows our invention applied to a picture-frame. Fig. 2 is a detached side view of the hanger.

The letter A designates the picture-frame, and B a cord for suspending the frame. To each end of the cord B is applied a wire hanger, 30 C, for attachment to the frame A, the hanger being, in this example, provided with a hook, f, of suitable character to engage a staple on the frame.

35 E designates an eye in the hanger, through which the picture-cord B passes, and f' a hook whereby the cord is held against longitudinal displacement. The eye E is situated interme-

diate of the ends of the wire composing the hanger, and it is produced by coiling the wire at that point, a series of coils being preferable, 40 with a view to elongate the eye.

The hook f' is at the end of the wire opposite to the hook f, or its substitute, and it has a sharp end for piercing the cord B. The sharp end of the hook f', however, is not essential 45 when a thin wire is used, inasmuch as the hook is in that case at once adapted to pierce the cord.

In applying the hanger C to use, the cord is drawn through the eye E and the hook f' 50 is forced into the cord, as indicated in Fig. 2, and hence the cord is firmly retained in position, while it may be readily adjusted to the desired length.

The construction of the hanger C permits of 55 its being made of a single piece of wire, and hence the cost of the manufacture is reduced to a minimum.

What we claim is—

A picture-hanger consisting of a single piece 60 of wire coiled intermediate its ends to form an eye for the passage of the picture-cord, one end of said wire being formed with a hook to pierce the cord for attaching the hanger, and the other end constructed to support the picture-frame, substantially as described.

In testimony that we claim the foregoing we have hereunto set our hands and seals this 21st day of February, 1880.

MICHAEL RAUGHTIGAN. [L. S.]
EDWIN OLDFIELD. [L. S.]
